United States Patent Office

Des. 224,130

Patented July 4, 1972

224,130

PHOTOGRAPHIC TIMER

Keith N. Swanson, 112 W. Cota St.,
Santa Barbara, Calif. 93101

Filed Aug. 31, 1970, Ser. No. 24,783

Term of patent 7 years

Int. Cl. D10—03

U.S. Cl. D42—7

FIG. 1

FIG. 2

FIG. 1 is a front perspective view of a photographic timer showing my new design; and

FIG. 2 is a rear perspective view, with the power cord shown fragmentarily for convenience of illustration.

I claim:

The ornamental design for a photographic timer, as shown and described.
